LOOM WIND-UP RATCHET

William N. Conway, North Grafton, Mass., assignor to
Draper Corporation, Hopedale, Mass., a corporation
of Maine

Filed May 13, 1964, Ser. No. 79,956

Term of patent 14 years

(Cl. D92—15)

FIGURE 1 is a front view of a loom wind-up ratchet showing my design;

FIGURE 2 is a rear view thereof;

FIGURE 3 is a side elevational view thereof;

FIGURE 4 is a cross-sectional view taken along the lines and arrows IV—IV of FIGURE 1.

I claim:

The ornamental design for a loom wind-up ratchet, substantially as shown.
